UNITED STATES PATENT OFFICE.

DAVID H. WILSON, OF PHILADELPHIA, PENNSYLVANIA.

STYLUS-BAR MOUNTING FOR REPRODUCERS.

1,390,964.

Specification of Letters Patent. Patented Sept. 13, 1921.

Original application filed June 1, 1920, Serial No. 385,800. Divided and this application filed February 7, 1921. Serial No. 443,232.

To all whom it may concern:

Be it known that I, DAVID H. WILSON, a citizen of the United States of America, residing at 6031 Trinity street, Philadelphia, in the county of Philadelphia and State of Pennsylvania, have invented certain new and useful Improvements in Stylus-Bar Mountings for Reproducers, of which the following is a specification.

10 This invention relates to phonographs, and has special reference to reproducers for such instruments.

15 More particularly the invention relates to the stylus bar mounting for reproducers and forms a division of my prior and copending application filed June 1, 1920, and bearing the serial number 385,800.

20 One important object of the invention is the provision of an improved arrangement 20 of the needle holding parts of a phonograph reproducer.

25 A second important object of the invention is the provision of an improved adjustable elastic fulcrum for the stylus bar or needle lever of a phonograph reproducer.

With the above and other objects in view, as will be hereinafter apparent, the invention consists in general of certain novel features of construction and combinations 30 of parts hereinafter fully described; illustrated in the accompanying drawings and specifically claimed.

35 In the accompanying drawings like characters of reference indicate like parts in the several views, and:—

Figure 1 is a side elevation showing the improved arrangement of needle holding parts as attached to a phonograph reproducer.

40 Fig. 2 is a face view of said parts.

Fig. 3 is an end view thereof.

Fig. 4 is a perspective view thereof.

45 In the embodiment herein shown there is disclosed a portion 19 of a reproducer casing and part of a diaphragm 14. Projecting from the casing 19 are spaced parts 22 which are connected at their outer ends by a bridge piece 23 having a centrally disposed threaded aperture 24. Through this 50 apertures passes a thumb screw 25 having a reduced end which engages in an opening in a bowed leaf spring 26 one end of which is fixed to a needle lever 27 while the other end slides freely thereon. On the under 55 side of the lever is secured a cantaliver leaf spring 28 the free end of which lies beneath

the spring 26 and rests on the casing member 19.

Secured to the inner end of the lever, which overlies the center of the diaphragm 60 14, is a screw 29 which passes through the diaphragm 14 and has nuts 30 on each side of said diaphragm to connect the lever and diaphragm in adjusted relation.

Thus by means of the thumb screw 25 the 65 tension of the spring fulcrum may be varied at will and the action of the needle lever on the diaphragm properly adjusted as desired.

The needle lever is provided in the usual manner, with a needle receiving opening 31 70 and set screw 32 for holding needles therein.

There has thus been provided a simple and efficient device of the kind described and for the purpose specified.

Having thus described the invention, what 75 is claimed as new is:—

1. In a phonograph reproducer, a casing, a pair of posts extending outwardly from said casing, a bridge piece extending across the ends of said posts, a needle lever passing 80 between said posts and beneath the bridge piece, a spring fulcrum for said lever bearing against said bridge piece and a leaf spring bearing on said lever and casing.

2. In a phonograph reproducer, a casing, 85 a pair of posts extending outwardly from said casing, a bridge piece extending across the ends of said posts, a needle lever passing between said posts and beneath the bridge piece, a spring fulcrum for said lever bearing against said bridge piece, a leaf spring 90 fixed to said lever and bearing against the casing beneath the fulcrum and means to adjust the tension of said spring fulcrum.

3. In a phonograph reproducer, a casing, 95 a pair of posts extending outwardly from said casing, a bridge piece connecting the outer ends of said posts and provided with a centrally disposed threaded aperture, a needle lever passing between said posts and beneath said bridge piece, a spring between the needle lever and the casing and located between said posts, a second spring between the bridge piece and the needle lever, and a thumb screw passing through the threaded 100 aperture and bearing against the second spring whereby to vary the tension on the second spring and thereby, the tension of the first spring.

110 In testimony whereof I have affixed my signature.

DAVID H. WILSON.
